JOURNAL LUBRICATOR DISTRIBUTOR

James J. Hennessy, Montclair, N. J.

Application January 13, 1943, Serial No. 472,189

4 Claims. (CL. 308—84)

The invention relates to railway axle journal lubricators of the type illustrated in patent to the present inventor, No. 2,260,520, issued October 28, 1941, in which lubricant is pumped from the bottom of the oil box to the face of the journal and is spread over the lower portion of the latter to be carried by the journal to the bearing resting on the upper portion of the journal.

The main object of the invention is to provide a simple, economical, effective structure for distributing the lubricant evenly over a substantial area of the lower portion of the journal and to maintain a desired contact between the lubricant distributing members and the journal irrespective of variations in the height of the journal in the box and in variations in inclination of the journal longitudinally of the box and irrespective of wear on the journal engaging parts.

Another object of the invention is to construct a distributor of substantial area so that it may be readily inserted beneath a journal while the same is in the box without detracting from a firm thrust of all of the distributor parts against the face of the journal after the assembly is completed.

These and other detail objects of the invention as will appear from the following description are attained in the structure illustrated in the accompanying drawing, in which—

Figure 1 is a longitudinal vertical section through an A. A. R. (American Association of Railroads) journal box and a distributor embodying the invention, the adjacent portions of the journal and the lubricant pump being shown in elevation.

Figure 2 is a top view of the distributor with the box sides being shown in section and portions of the pump beneath the distributor being illustrated also. Parts of the distributor assembly are removed to more clearly illustrate the structure. Figure 3 is a vertical transverse section taken approximately on the line 3—3 of Figure 2.

Figure 4 is a view corresponding to Figure 1 but drawn on a smaller scale and illustrating the manner of application and removal of the distributor to and from the journal.

The journal 1 forms the end portion of the axle and is provided with a collar 2. The box has side walls 3 and a bottom wall 4 with its outer end curved upwardly as at 5 to form the lower edge 6 of the box opening 7. The lubricator pump comprises a substantially rigid body portion 8 resting on the box bottom wall and having

laterally extending inclined ears 9 to which are pivoted a series of compound levers 10 and 11, the upper ends of the latter-mentioned levers engaging the journal collar 2. The inner ends of levers 10 engage the outer ends of plungers 12 which are thrust to the left by coil springs 13. Plungers 12 operate pistons (not shown) in the pump body to draw in oil provided in the lower portion of the box and to discharge it to the distributor.

The journal and box parts illustrated are of ordinary construction. The pump parts illustrated are disclosed in an earlier application filed by the present inventor June 1, 1942, Serial No. 15 445,299, now Patent No. 2,331,835, issued October 12, 1943.

Mounted on the pump body is a distributor unit comprising a lower arm 14 having a ball-shaped terminal seated in a socket in the top of 20 the pump and a plate 15 of cruciform outline and a concave upper surface provided with ridges arranged to contact with the lower face of the journal. A lubricant conduit 16 leads from the lower end of arm 14 to outlets 17 in the upper 25 face of plate 15. The lower end of arm 14 has an upwardly facing spring seat 18 and the plate 15 has a downwardly facing spring seat 19. A coil spring 20 is compressed between seats 18 and 19 and thrusts the hinged parts away from each other to maintain them in the position shown in Figure 1. The movement of the hinged parts away from each other under the thrust of spring 20 is limited by the abutment of shoulders X at the hinged end of the unit. This distributor 30 unit embodies features disclosed in an earlier application filed by the present inventor September 6, 1941, Serial No. 409,761, now Patent No. 2,359,643, issued October 3, 1944.

Associated with parts 14 and 15 is an extension 40 structure including a central frame comprising a channel-like plate 21 with downturned flanges 22 projecting longitudinally of the device beyond the ends of the plate. A coil spring 23 is compressed between seat 18 and the lower face of plate 21 to thrust the latter upwardly against the bottom of plate 15. Plate 21 has a central hole H through which spring 20 extends to engage its seat 19.

A pan-like member 24 surrounds each end arm 50 of plate 15 and extends lengthwise of the device beyond the arms. Each member 24 has a U-shaped reinforcing angular strip 25 with the upright flanges of the legs of the strip extending alongside the outer portions of flanges 22 and pivoted thereto at 26. The horizontal flanges of

the legs of each U and the adjacent portion of the pan member extend beneath the lower edges of flanges 22 and limit the downward movement of the outer portions of the pan members about their pivots 26. The outer ends of the pan members are free to swing upwardly from the horizontal position shown in Figure 1 to the position shown in Figure 4 to facilitate the insertion and removal of the distributor through the end opening in the box and while the journal and the box are still assembled.

A series of felt pads 27 are held together by bolts 28 and are carried in members 24. Some of the pads have depending ears 29 inserted through slots 30 in pans 24 to maintain the assembly of the pads and their carriers when the device is not in place in a journal box. The contour of these pads is such that their upper edges are thrust against the lower portion of the journal and the pads absorb oil discharged from plate 15 and, when saturated, distribute this oil to the journal, thus providing an even supply of oil throughout substantially the entire lower portion of the journal.

With this construction, the rigid central distributor plate 15 and the carrier supported pads are yieldingly thrust against the journal to provide uniform contact throughout the area of the distributor and irrespective of variations in the manufacture of the parts which may be formed without substantially machining or fitting and irrespective of the relative positions of the pump and journal in the box. The device is simple and the parts are held in functioning position by the two helical springs, each spring supported part being movable independently of the other. As indicated above, the parts are readily inserted and removed into and out of functioning position.

The details of the structure may be varied without departing from the spirit of the invention, and the exclusive use of those modifications of the described structure which come within the scope of the claims is contemplated.

What is claimed is:

1. In combination with a device for lubricating a railway journal and including a rigid distributor plate of restricted area for application to the journal and provided with supporting means, felt pads disposed to engage the journal at the sides of said plate, and structure yieldingly supporting said pads independently of said plate and means and comprising a frame and pad carriers mounted thereon and a yielding support for the frame and carriers, the mounting of the carriers on the frame providing for the inclination of said carriers and the pads thereon relative to said plate and frame and relative to each other to facilitate the insertion and removal of the plate, frame and pads through the space between the

journal and the bottom of the box to which it is applied.

2. In a device for lubricating a railway journal, a horizontally disposed frame defining an opening adapted to receive the support for a central distributor applied to the journal, a yielding support for the frame applied thereto at opposite sides of said opening and arranged to clear said distributor support and to thrust the frame towards the journal, a pad carrier normally extending horizontally lengthwise of the frame beyond each end of the latter and pivoted to the frame to swing upwardly about each end of the frame to facilitate application and removal of the device through the restricted space between an axle journal and box, and means securing said carrier against pivotal movement downwardly from a normal horizontal position.

3. In a device for lubricating a railway journal, a central frame member consisting of a channel having a horizontal web and downturned flanges, the flanges extending longitudinally of the device beyond the ends of the web, there being an opening of substantial area in said web for receiving a separate distributor part extending from below the device upwardly towards the journal, a yielding support for said frame, pads for application to a journal, carriers for said pads comprising pan-like members extending longitudinally of the device beyond said frame and having horizontal arms extending inwardly from the ends of said frame and abreast of said channel flanges, pivots through said arms and flanges at points spaced substantially from the inner ends of said arms, and interengaging elements on the inner ends of said arms and the adjacent portions of said frame for limiting the pivoting movement downwardly of the outer portions of said members.

4. In combination with a device for lubricating a railway journal which includes a rigid distributor plate of restricted area for application to the journal and having a downwardly inclined conduit hinged at one side and terminating at its lower end in a portion arranged to rest on a pump body and provided with a spring between said plate and conduit for thrusting the same apart; a horizontally disposed frame apertured to surround said spring, carriers hinged to the ends of said frame and extending outwardly therefrom, fibrous pads mounted on said carriers to engage the journal outwardly from the edges of the distributor plate, said carriers being pivoted on said frame to swing upwardly on their pivots from a normal horizontal position but being held against swinging downwardly from said position, and a spring arranged to seat on said conduit portion and to engage said frame to hold said pads against the journal.

JAS. J. HENNESSY.
